ASSIGNORS TO FARMERS NATIONAL BANK, TRUSTEE, OF GREENVILLE, OHIO, A
CORPORATION OF OHIO

FUELIZER FOR HYDROCARBONS

Application filed November 25, 1924. Serial No. 752,273.

Our invention relates to fuel burners, more particularly to a fuelizer for burners in which the heavier grades of fuel oil such as kerosene, distillate and the like may be vaporized and burned with a silent, clean, blue flame, there being no carbon deposits or sticky residue left from the fuel since the combustion is complete. Fuel of this class which is vaporized by being in continuous contact with

10 the rapidly moving current of a gaseous medium other than fuel vapor does not decompose enough to form any tar or solid carbon deposits.

The perfect combustion of heavy liquid hydrocarbons and the volatile portion of solid hydrocarbons present many obstacles owing to the difficulty of preparing a homogeneous explosive mixture of combining proportions previous to ignition.

20 In the normal combustion of any hydrocarbon the fuel burns entirely from the molecule. There is a steady, orderly, progressive hydroxylation which always results in an entirely blue, transparent flame that is comparatively non-luminous and non-radiant. In such a combustion there is no dissociation of the fuel molecules, consequently no carbon is freed, therefore the flame is of an almost entirely electrical character, practically indistinguishable from the purely electrical blue flame.

The principal object of this invention is to provide a vaporizer that will perform the above named functions; another object is to

35 provide a fuelizer of this class for burners particularly for generating steam in automobile steam power plants, but the principles involved are very broad and may be embodied in burners of many kinds; another

40 object of the invention is to provide a fuelizer of this class which mixes the fuel and air in combining proportions and by centrifugal or inertia separation throws the fuel against a surface heated partially or entirely by contact with the flame of the burner or partially

or entirely by the flame of a pilot burner, the said heated surface being scrubbed by the air thereby preventing the cracking of fuel and subsequent deposition of carbon; another object of the invention is to provide a means whereby the fuel vapor as fast as formed mixes with the air and passes through the grating or nozzle from which it is burned; another object of the invention is to provide a burner of this class in which the air and fuel is subjected to a centrifugal whirling motion tending to throw the heavier portions adjacent the heated surface and the lighter portions not being subjected to the same degree of heat.

With these and other objects in view as will appear hereinafter our invention consists of certain novel features of construction, combination and arrangement of parts and portions as will be hereinafter described in detail and particularly set forth in the appended claims, reference being had to the accompanying drawings and to the characters of reference thereon which form a part of this application in which:

Figure 1 is a diagrammatic elevational view of the fuelizer shown fragmentarily, showing particularly the vaporizer and air control mechanism; Fig. 2 is a sectional view through the middle of the vaporizer showing some of the parts in elevation and certain portions of the parts in elevation broken away and in section to facilitate the illustration; Fig. 3 is a transverse sectional view thereof through 3-3 of Fig. 2; Fig. 4 is a similar view through 4-4 of Fig. 2; Fig. 5 is a similar view through 5-5 of Fig. 2 showing some of the parts and portions in full plan to facilitate the illustration; Fig. 6 is a similar view through 6-6 of Fig. 2 and Fig. 7 is a fragmentary sectional view through 7-7 of Fig. 5.

Similar characters of reference refer to similar parts and portions throughout the several views of the drawings.

The vaporizer 1, air supply conductor 2,

pilot combustion chamber 3, circular grating 4, chamber 5, spark plug 6, main fuel carbureter 7, pilot fuel carbureter 8, conductor 9, main air inlet conductor 10, air inlet valve 11, and mixer 12, constitute the principal parts and portions of our fuelizer for burners.

The vaporizer is shaped as shown best in Figs. 1 and 2 of the drawings, particularly Fig. 2. It consists of a main vaporizing chamber 1^a which is provided with a central core 1^b therein. In one side is provided an orifice 1^c which connects with the conductor 7^a from the main fuel carbureter 7, shown only in Fig. 1 of the drawings. This carbureter 7 is the main carbureter for the fuel supply. It is provided with a pressure tube 7^b communicating with the air inlet pipe 10. It will be here noted that the air inlet pipe 10 is provided with a fan to provide air under pressure in the conductor tube 2. Secured in the interior of the wall of the vaporizer 1, preferably integral therewith, in the chamber 1^a is a rib 1^d which is in involute form and serves to prevent the fuel from the carbureter from running down on the wall of the vaporizer 1 as it enters the vaporizer from the carbureter 7. This vaporizer 1 is provided at its normally lower side with an annular chamber 1^e which does not communicate with the interior of the vaporizer directly. Communicating with this chamber 1^e is a conductor 1^f which connects therewith on a tangent as shown best in Fig. 5 of the drawings. Communicating with this conductor 1^f is the conductor 2 which is provided with a contracted nozzle portion 2^a which enters a small opening in the conductor 1^f. This conductor 2 is provided with a carbureter 8 as shown only in Fig. 1 of the drawings which carbureter 8 is of a conventional type and adapted to feed fuel to the conductor 2 in the proper proportion to the air passing through the conductor 2. Therefore the fuel consisting of air from the air conductor 10 and hydrocarbon from the carbureter 8 passes through the nozzle 2^a, conductor 1^f into the annular chamber 1^e on a tangent and assumes a whirling motion in said annular chamber. In the lower wall of this annular chamber 1^e is provided an upwardly extending orifice member 1^g shaped as shown best in Figs. 5 and 7 of the drawings which is adapted to receive the mixed fuel and air which passes downwardly through the orifice 1^h in the member 1^g and down into the pilot grating chamber 5. It will be here noted that the orifice 1^h is positioned inwardly from the wall forming the outer and upper walls of the chamber 1^e, and upwardly from the wall forming the upper side of the chamber 5 so that the heavier fuels will not pass down but will continue on said walls, by reason of the circulating current of gases, and be heated by conduction and formed into a vapor be-

fore passing down through the orifice 1^h into the chamber 5, it being noted that a passage for the heavier fuels is provided inwardly and upwardly from the portion in which the orifice is formed, said portion being also inclined upwardly in the direction of the circulating gases. The chamber 5 is provided with an annular grating partition 4 providing a combustion chamber 5^a in the interior of the partition 4. In this partition 4 are a plurality of slots or holes 4^a extending therethrough on an angle so that the fuel in passing from the chamber 5 into the combustion chamber 5^a passes through the partition on an angle to its axis thus providing additional whirling motion to and homogenizing of the combustible mixture as it enters the combustion chamber 5^a. Mounted in the lower side of this combustion chamber 5^a is a spark plug 6 which is connected with an electrical system of a conventional type whereby it is provided with intermittent sparks for igniting the fuel in the combustion chamber 5^a and provides a means whereby if the fuel mixture should become wet or foul in any manner and the pilot fire extinguished the spark plug will reignite the fuel in the combustion chamber 5^a. It will be here noted that complete combustion takes place in the combustion chamber 5^a and the fuel is consumed in a blue flame the burned gases and heat passing up through the small rounded opening 1ⁱ into the main vaporizer chamber 1^a and passes on up in a whirling manner thus tending by reason of the centrifugal force to cause the burned gases to move adjacent the inner wall of the casing 1, passing around the core 1^b and passing out through the conductor 9.

It will be noted that the fuel burner hereinbefore described and termed a pilot burner burns continuously keeping the walls of the pilot vaporizer and main burner vaporizer of the proper heat at all times and forming the foundation and circulating medium for vaporizing the main fuel which passes in through the orifice 1^c from the carbureter 7 shown in Fig. 1 and is picked up by the whirling motion of the burned gases from the combustion chamber 5^a and vaporized thereby and passes out with the burned gases in the conductor 9. Thus it will be noted that the fuel burned and whirling motion imparted to the burned gases in the combustion chamber 5^a forms the medium and vehicle for vaporizing the main fuel from the carbureter 7. The whirling motion of the burned gases in chamber 1^a causes the liquid fuel from carbureter 7 to rotate against the inner wall of vaporizing chamber 1^a adjacent to orifice 1ⁱ. This wall is heated by conduction from pilot combustion chamber 5^a by convection from the burned gases therefrom and by radiation from the core 1^b. The heat absorbed from the wall and from the current of hot

burned gases passing over the liquid causes it to vaporize and the vapor passes inwardly through the liquid to the current of burned gases by which it is swept out of vaporizing chamber 1^a as fast as formed to conductor 9. This fuel vapor passes through the conductor 9 into the fuel and air mixer 12 where it mixes with a proper and regulated quantity of air through the conductor 10 past the valve 11 through the Venturi tube 12^a. The Venturi tube 12^a is provided with a plurality of apertures 12^b through which the fuel passes and the air engages it at a contracted right angled position in the Venturi tube 12^a and the mixed fuel and air is conducted downwardly to the burner 13 which is preferably a convolute burner which starts the fuel whirling and it is burned in this whirling condition.

The operation of the fuelizer is as follows: Air under pressure from the fan passes down through the air conductors 10 and passes through the conductor 2 and fuel is admitted to the nozzle 2^a from the carburetor 8 and passes through the nozzle 2^a into the conductor 1^c which connects with the chamber 1^e on a tangent, therefore the fuel passes into the annular chamber 1^e on a tangent and assumes a whirling motion, whirling around in the annular chamber 1^e. The proper mixing of the fuel vapor and air is brought about in passing it through the orifice 1^h into the annular chamber 5 below. In the chamber 5 it continues its whirling motion, passes out through the holes or channels 4^a into the combustion chamber 5^a, burned and kept ignited by the spark plug 6. The gases from the complete combustion passing upwardly in a whirling motion in through the opening 1^l into the chamber 1^a, thereby heating the walls of chamber 1^a. The whirling motion of the burned gases in chamber 1^a causes the liquid fuel from carburetor 7 to rotate against the inner wall of vaporizing chamber 1^a adjacent to orifice 1^l. This wall is heated by conduction from pilot combustion chamber 5^a, by convection from the burned gases therefrom and by radiation from the core 1^b. The heat absorbed from the wall and from the current of hot burned gases passing over the liquid causes it to vaporize and the vapor passes inwardly through the liquid to the current of burned gases by which it is swept out of vaporizing chamber 1^a as fast as formed to conductor 9, then to the mixing chamber 12 through the orifices 12^c there mixing with the air from the main air conductor 10 in the Venturi tube 12^a and the mixed air and fuel passing downwardly to the burner 13 where it is burned in the ordinary manner.

Though we have shown and described a particular construction, combination and arrangement of parts and portions we do not wish to be limited to this particular construc-

tion combination and arrangement but desire to include in the scope of our invention the construction, combination and arrangement substantially as set forth in the appended claims.

Having thus described our invention what we claim as new and desire to secure by Letters Patent is:

1. In a fuelizer for hydrocarbons, a fuel and air pressure supply means, an annular vaporizing member, tangential conducting means for causing the fuel to whirl and circulate in the said annular vaporizing member, a combustion chamber communicating therewith, means for causing the burned gases to whirl, a chamber for receiving the same, heated by conduction, convection and radiation, and a main fuel supply communicating with said last mentioned chamber whereby fuel from the main supply intermingles with the burned gases from the combustion chamber and the main supply is completely vaporized.

2. In a fuelizer for hydrocarbons, a pilot burner, a chamber for receiving the burned gases from said pilot burner provided with a central solid heating core, a main fuel supply communicating with the chamber receiving the burned gases from said pilot burner, means for causing the fluids to whirl in said chamber, means for supplying fuel under pressure to said pilot burner, and other means for subjecting said fuel to centrifugal motion in said pilot burner.

3. In a fuelizer for hydrocarbons, a pilot burner, a chamber for receiving the burned gases from said pilot burner provided with a central solid heating core, a main fuel supply communicating with the chamber receiving the burned gases from said pilot burner, means for causing the fluids to whirl in said main vaporizing chamber, means for supplying fuel under pressure to said pilot burner, other means for subjecting said fuel to centrifugal motion in said pilot burner, and means for igniting the fuel in said pilot burner.

4. In a fuelizer for hydrocarbons, means for supplying a fuel mixture under pressure, an annular receiving chamber for said fuel mixture, an annular partition provided with a plurality of angularly positioned openings therethrough, means for igniting the fuel mixture on the interior of said partition, a chamber for receiving the burned gases from said receiving chamber provided with a central solid heating core, a main fuel supply communicating therewith, a conductor for the mixture of main fuel supply and burned gases, a Venturi tube for receiving the fuel supply from said vaporizing chamber and air under pressure through said Venturi tube.

5. In a fuelizer for hydrocarbons, means for supplying a fuel mixture under pressure, an annular receiving chamber therefor,

annular partition provided with a plurality of angularly positioned openings there-through, means for igniting the fuel on the interior of said partition, a chamber for receiving the burned gases from said receiving chamber provided with a central solid heating core, a main fuel supply communicating therewith, a conductor for the main fuel supply and burned gases, a Venturi tube for receiving the fuel supply from said vaporizing chamber, and air under pressure through said Venturi tube, and a burner communicating with said Venturi tube.

6. In a fuelizer for hydrocarbons, a vaporizer consisting of an outer casing, a central solid heating core extending therein, an annular chamber surrounding the outer side of the wall of the main chamber, another annular chamber communicating therewith, a partition therein provided with orifices therethrough, forming a central combustion chamber, contracted communicating means between said central combustion chamber and the main chamber, means for introducing fuel and air mixture under pressure on a tangent to said annular chamber, and tangential conducting means for continuing the whirling motion of said fuel and air mixture.

7. In a fuelizer for hydrocarbons, a fuel and air pressure supply means, an annular vaporizing member, tangential conducting means for causing the fuel to whirl and circulate in said annular vaporizing member, a combustion chamber communicating therewith, means for causing the burned gases to whirl, a chamber for receiving the same, and a main fuel supply communicating with said last mentioned chamber whereby fuel from the main supply intermingles with the burned gases from the combustion chamber.

8. In a fuelizer for hydrocarbons, an annular vaporizing member, means for conducting fuel tangentially therein for causing the same to whirl and circulate in said vaporizing member, a combustion chamber communicating therewith, means for causing the burned gases to whirl, and a main vaporizing chamber for receiving the burned gases.

9. In a fuelizer for hydrocarbons, a pilot combustion chamber, a main vaporizing chamber for receiving the burned gases from the pilot combustion chamber, means in connection with the pilot burner for causing the gases therefrom to whirl, and to whirl within the main vaporizing chamber, and a main liquid fuel supply communicating with said last mentioned chamber, the liquid fuel thereof being adapted to be vaporized by and intermingled with the burned gases from the combustion chamber, the gases from the pilot combustion chamber being the main source of gases within the main combustion chamber.

10. In a fuelizer for hydrocarbons, a combustion chamber, a vaporizing chamber communicating therewith and adapted to receive

hot burned gases from the combustion chamber, means for causing said hot gases to whirl within and against the peripheral portions of the inner walls of said vaporizing chamber, and means for directing fuel into said whirling gases and adapted to be forced by said gases against said walls.

In testimony whereof, we have hereunto set our hands at Los Angeles, California, this 13th day of November, 1924.
